UNITED STATES PATENT OFFICE.

BRUCE W. TRAYLOR, OF ALLENTOWN, PENNSYLVANIA.

INTERNAL-COMBUSTION ENGINE.

1,360,828.

Specification of Letters Patent. Patented Nov. 30, 1920.

Application filed July 29, 1919. Serial No. 314,092.

To all whom it may concern:

Be it known that I, BRUCE W. TRAYLOR, a citizen of the United States, resident of Allentown, Pennsylvania, have invented certain new and useful Improvements in Internal-Combustion Engines, of which the following is a specification.

My present invention relates to improvements in internal combustion engines and is 10 designed as an improvement on the form of engine disclosed in Letters Patent of the United States granted to me on the 31st day of July 1917 #1,234,971.

One object of the invention is to provide 15 an engine with a simple and durable over head valve construction in which is provided efficient lubricating means for insuring proper lubrication of the various moving parts of the valve operating mechanism.

Another object is to so arrange the intake 20 passages that the number of joints will be reduced and the passages water jacketed thereby heating the incoming combustible mixture and preventing any condensation of 25 gasolene.

With these and other objects in view the invention includes the novel features of construction and arrangement and combination of parts hereinafter described and particularly defined by the appended claims.

An embodiment of my invention is illustrated in the accompanying drawings in which—

Figure 1 is a transverse vertical sectional 35 view of my improved engine.

Fig. 2 is a part sectional elevation.

Fig. 3 is a sectional plan of a part of the cylinder block.

Fig. 4 is a side elevation partly in section 40 of a part of the cylinder block with the head removed, and

Figs. 5, 6, and 7 are detail views.

Referring by reference characters to these drawings the numeral 1 designates the cylinder casting constructed *en bloc* and which may comprise any number of cylinders, twelve with six on each side being a desirable number. The cylinders individually are designated 1^a and within each pair of 50 cylinders works a double piston 2 provided with a wrist pin 3 connected by a single pitman to the crank shaft 4.

The cylinder block head is provided with a central longitudinal cam shaft chamber 5 in which is located the cam shaft 6 jour-

naled at or near its opposite ends in suitable bearings 6^a in the end walls of the cam shaft chamber.

The cam shaft is operated from the crank shaft through the vertical shaft 7 at the 60 end of the engine which is operatively connected to the crank shaft and engine shaft by suitably timed gearing of any approved type.

Secured upon the top of the cam shaft 65 chamber and completely closing the same is a cover member 8 which carries a plurality of brackets 8^a on each side.

Each set of brackets carries a longitudinal hollow shaft 9 which is closed at both 70 ends, and which is preferably held stationary by being pinned to one or more of the brackets.

These shafts support the rocker arms 10 which have their outer ends suitably adjustably connected to the stems 11^a and 12^a of the inlet and exhaust valves 11 and 12 said inlet and exhaust valves being located along the outer sides of the cylinder block as shown.

The rocker arms are provided with projections or arms 10^a which overlie the upper 80 ends of hollow plungers 13 guided in vertical passageways formed in the cam shaft cover 8 and which bear, at their lower ends, 85 on the cams 6^b of the cam shaft.

Oil under pressure is supplied to the oil chamber 5 from an oil pump of the ordinary or any desired construction such as commonly used in connection with automobile 90 engines, through the supply pipe 14.

From the oil chamber 5 a portion of the oil is diverted to lubricate the contact surfaces of the plungers and rocker arms and to this end the plungers are provided with 95 small oil ports or passages 5^a and 5^b.

The oil escaping through these openings will pass onto the head of the engine and some of it will reach the felt washers 15 encircling the valve stem guides, which will 100 lubricate the valve stems through the oil passages 15^a.

Any surplus oil on the cylinder heads will be returned to the oil sump by way of the casing of the gears driving the cam shaft.

To effect the lubricating of the rocker arms certain of the brackets, as for example the middle ones, are provided with oil passages 8^b which communicate with the interior of the hollow shafts 9 to maintain the latter 110

filled with oil, and the portions of the shafts upon which the rocker arms are pivoted or journaled are provided with oil passages 9^a by which oil passes from the interior of 5 the hollow shafts to lubricate the rocker arm bearings.

The front ends of the shafts are provided with small oil ports through which surplus oil escapes into the gear casing, lubricating 10 the gears on its way back to the sump.

The rocker arms and associated parts are completely inclosed by the dust excluding cover 16 which covers the complete head of the engine.

15 As above stated the inlet and exhaust valves are located along the outer sides of the cylinder head. The exhaust valve chambers communicate by the passages 17 through the side walls of the cylinder head with the 20 exhaust manifolds 18 one on each side.

To supply the combustible mixture to the inlet valve chambers I provide the cylinder head with a pair of longitudinal chambers 19 extending substantially the full length of 25 the cylinder head and between the cam shaft chamber and the valve chambers, these chambers communicating by passages or ports 19^a with the inlet valve chambers, said chambers 19 being also connected by the internal passages 19^b with a common intake port in the side of the cylinder block to which an elbow 20 may be bolted for carbureter connection.

By the above construction I provide a 35 very compact arrangement, secure a direct discharge of the exhaust products, eliminate any requirement for an intake manifold, provide for the heating of the combustible mixture and avoid all danger of condensation of gasoline from the mixture in its 40 passage from the carbureter to the inlet valve chambers.

Having thus described my invention what I claim is:—

45 1. In an internal combustion engine having overhead valves, a closed oil chamber in the cylinder head, a cam shaft rotatably mounted in said chamber, means for supplying oil to said chamber under pressure, valve 50 operating rocker arms mounted on the cylinder head, and means for conducting oil from said chamber to the rocker arm bearings.

55 2. In an internal combustion engine having overhead valves, an oil chamber in the cylinder head, a cam shaft rotatably mounted in said chamber, a cover member for said chamber, plungers guided in said cover member and coacting with said cam shaft, valve 60 operating rocker arms pivotally mounted on said cover member and having parts bearing on the upper ends of the plungers, oil passages through said plungers for conducting oil to the upper faces thereof, and means for supplying oil under pressure 65 to said oil chamber.

3. In an internal combustion engine having overhead valves, an oil chamber in the cylinder head, a cam shaft located therein, a cover member having vertical guide openings, plungers mounted in said openings and 70 coacting with said cam shaft, a hollow shaft supported by said cover member, means for conducting oil from said chamber to said hollow shaft, rocker arms pivoted on said hollow shaft, oil passages through the hollow shaft for lubricating the rocker arm bearings, and means for supplying oil under pressure to said oil chamber. 75

4. An internal combustion engine having two rows of cylinders and a longitudinally 80 disposed oil chamber arranged centrally of the head thereof, a cam shaft mounted therein, a cover member for said chamber having guide openings above said cam shaft, plungers working in said guide openings and coacting with said cam shaft, a pair of shafts carried by said cover member, rocker arms journaled on said shafts and having parts overlying the upper ends of the plungers, means for supplying oil to said chamber under pressure, and means for conducting oil 85 from said chamber to the rocker arm bearings. 90

5. An internal combustion engine having two rows of cylinders and a longitudinally 95 disposed centrally arranged closed oil chamber in the cylinder head, a cam shaft rotatably mounted in said chamber, plungers guided in openings in the top of said chamber and cooperating with said cam shaft, a 100 pair of shafts supported above said chamber, rocker arms journaled on said chamber, and having parts overlying the plungers, means for supplying oil under pressure to said chamber, and means for conducting oil 105 from said chamber to the rocker arms bearings.

6. An internal combustion engine having two parallel rows of vertical cylinders and a single cylinder head, with inlet and exhaust 110 valve chambers located near the outer side of each row, exhaust ports opening directly outwardly through the outer sides of the cylinder heads, longitudinal intake passages located in the head between the rows of inlet and exhaust ports and having branches leading to the inlet valve chambers, and means for leading the combustible mixture to said 115 inlet valve chambers.

7. An internal combustion engine having 120 two parallel rows of vertical cylinders and a single cylinder head with inlet and exhaust valve chambers located near the outer side of each row, exhaust ports opening directly outward through the outer sides of the cylinder heads, longitudinal intake passages located in the head between the rows of inlet and exhaust ports and having branches leading to the inlet valve chambers, an intake 125 port in the side of the cylinder block below 130

the head, and independent intake ducts leading inwardly and upwardly from said intake port to said intake passages.

8. An internal combustion engine having two parallel rows of vertical cylinders of the L head type and a cylinder head having vertically disposed cylindrical inlet and exhaust valve chambers, said chambers being arranged in two parallel rows, arranged near the outer sides of the cylinder heads respectively, valve cages carrying valves located in

said valve chambers, exhaust ports opening directly outward through the cylinder head from said exhaust chambers, a pair of longitudinal intake passages in said head between 15 the rows of valve chambers and communicating therewith respectively, and means for supplying combustible mixture to said longitudinal passages.

In testimony whereof, I affix my signature. 20

BRUCE W. TRAYLOR.
